UNITED STATES PATENT OFFICE.

ROCKWELL SAYER, OF CHICAGO, ILLINOIS.

DRESSING-CASE.

SPECIFICATION forming part of Letters Patent No. 323,739, dated August 4, 1885.

Application filed July 15, 1882. (No model.)

To all whom it may concern:

Be it known that I, ROCKWELL SAYER, a citizen of the United States, residing at the city of Chicago, in the county of Cook, in the 5 State of Illinois, have invented certain new and useful Improvements in Dressing-Cases, which are fully set forth in the following specification, reference being had to the accompanying drawings, in which—

10 Figure 1 is a front elevation of my improved dressing-case, the front of the wardrobe portion being partly broken away so as to show the clothes-hanging device. Fig. 2 is a section on the line $\alpha\alpha$ in Fig. 1, the partition 15 being partly broken through so as to show the clothes-hanging device. Fig. 3 is a section on the line $\gamma\gamma$ in Fig. 1 looking downward, showing the dressing-table, which slides out.

The same letters denote the same parts in 20 all the figures.

My invention relates to household furniture, and particularly to that class of furniture in which a dressing-case is combined with a wardrobe and drawers and other receptacles; and it consists in the several devices and 25 combinations of devices, which will be fully set forth hereinafter, and definitely pointed out in the claims, the object being to serve in one article of furniture a greater variety of 30 uses, and those more conveniently than in any construction or arrangement heretofore devised.

The idea of having a dressing-table in combination with a wardrobe and mirror and chiffonier distinguishes my invention from anything heretofore produced, and renders it a 35 dressing-case.

In the drawings, A denotes the wardrobe part of my improved dressing-case. It is constructed of greater depth than is ordinary in 40 household wardrobes, thereby admitting garments to be hung in edgewise to the front on shoulders, instead of crosswise. At a convenient height a rod, A', supported at its ends is 45 extended from side to side of it, about halfway between the front and rear. From this rod are suspended, at right angles to its length, a number of clothes-hanging bows or hooks, of a form already well known—such as to support 50 the garment on two sides. These are arranged parallel to each other, and evidently

need be at very short distances apart, so that a much greater number of garments can be hung up than is possible with the ordinary arrangement of hooks at the same time that the shape 55 of each garment is much better preserved, each is accessible without disturbing the others, and all are in view at once on opening the door of the wardrobe. A mirror, A², with its frame constitutes the door of the 60 wardrobe, and a drawer, B, may be arranged under it.

In the upper part of the chiffonier-division of the dressing-case is a shelved closet, C, which may be used as a book-case or for any 65 other purpose that may be preferred. Below this closet are a series of drawers, D.

In place of one of the drawers D, at a convenient height, I set a dressing-table, E, which also may be used as a writing-desk, arranged 70 to be drawn out a convenient distance, with pigeon-holes, &c., in back part; and having a hinged front, E', which hangs down when the dressing-table is drawn out for use, and which stands up like the front of a drawer, so as to 75 close the space in front of the dressing-table when it is pushed back. This device is illustrated by full and dotted lines in Fig. 2. The front piece, which obscures the dressing-table when shut up, may drop down, when it is open, 80 at right angles with the table, as shown; or it may drop down only to a level with the table, and thereby form an extension to the table; or the space may be obscured by rollers or slides or other devices. 85

The dressing-table E is so constructed in connection with the chiffonier that it can slide back into place with all of the toilet articles upon it, so that they are all protected when still on the dressing-table as fully as if placed 90 in a drawer.

The drawers, together with the dressing-table, may be locked at once by means of a cleat extending up and down at one side.

For a dressing-case, the arrangement just 95 described is highly convenient, as a person can stand before the mirror and have the appliances of the toilet within easy reach of the hand.

The cornice G, that rises above the case in 100 front for ornamentation, may be constructed so that it may be moved to the back or front

at pleasure. When on back side, as shown in Fig. 2, it leaves the front of case easy to be dusted off on top, and also accessible and useful as a place to put books, papers, busts, &c.

5 I am aware of the arrangements shown in Figs. 315, 329, and 340 of Tabbert & Shaw's collection of designs for fashionable furniture, published by The Cabinet Maker and Art Furniture, No. 5 Finsbury Square, London, 1881; and I do not claim such an article of furniture as is represented in either of these figures. Neither of them shows a sliding dressing-table or a drawer with a hinged front, such as are combined in the structure which

15 I have described.

What I claim as my invention, and desire to secure by Letters Patent, is—

1. An article of furniture comprising, first, a full-length wardrobe, A, having a door with a full-length mirror in its front; and, second, 20 a chiffonier arranged at the side of the wardrobe and provided with the sliding dressing-table E, having the hinged drawer-front E', substantially as and for the purposes described.

2. The chiffonier containing the drawers D, of ordinary construction, and the drawer E, having a sloping bottom, and the front E', hinged to the bottom, substantially as and for the purpose described. 25

ROCKWELL SAYER.
